UNITED STATES PATENT OFFICE.

CURTIS A. LIMBACH, OF BROOKLYN, NEW YORK, ASSIGNOR TO J. H. WHITE MANUFACTURING COMPANY, OF BROOKLYN, NEW YORK, A CORPORATION OF NEW YORK.

COVER FOR ELECTRIC-LAMP SOCKETS.

1,255,030.

Specification of Letters Patent. Patented Jan. 29, 1918.

Application filed September 1, 1917. Serial No. 189,235.

To all whom it may concern:

Be it known that I, CURTIS A. LIMBACH, a citizen of the United States, residing at the borough of Brooklyn, in the county of 5 Kings, city and State of New York, have invented an Improvement in Covers for Electric-Lamp Sockets, of which the following is a specification.

My invention relates to socket covers for 10 use in lighting fixtures. Socket covers in general use are constructed to act both as a cover for the lamp socket, and as a holder for the shade or bowl, that is, the upper end of the socket projects through an opening 15 in the top of the cover, which cover rests upon the top of the socket, while its lower part receives the neck or flange of the bowl, being provided with set screws to clamp and support the shade.

20 In some fixtures a separate shade ring or holder is employed to which the lower part of the socket is detachably secured, usually by a thread upon the socket screwed into a threaded central opening in the ring or 25 holder, and with such fixtures it has not been customary to make use of a socket cover.

The object of my present invention is to 30 provide a cover for the sockets of this character, whereby the appearance of the fixture is greatly improved, and the cover can be readily attached without the necessity of making any change whatever in either the socket or shade holder.

In the accompanying drawing:

35 Figure 1 is an elevation of my improved socket cover.

Fig. 2 is a plan view of the same.

Fig. 3 is an elevation showing the cover in position upon a fixture.

40 Fig. 4 is an elevation of a lamp socket, and

Fig. 5 is a plan view of a shade ring or holder.

Similar reference characters denote like 45 parts in the several views.

10, indicates the socket cover which is of sheet metal pressed to shape and open at both top and bottom. The opening at the bottom is of larger diameter than the open-

50 ing at the top. The top portion is without flange or curvature; at a predetermined distance from the top it is curved outwardly, and at the extreme lower end is preferably curved downwardly at an inclination.

55 Where a socket is provided with a key,

this cover 10 may be provided with a vertical open ended slot 11 to fit over the shank of the key.

In Figs. 4 and 5 of the drawing, I have separately illustrated the character of socket 60 and shade ring or holder with which my improved cover is designed for use, and in Fig. 3 I have illustrated these parts assembled.

12, denotes the lamp socket provided at its 65 lower part with an exterior screw-thread 13, and at its upper part with an exterior annular band or rib 14.

I have shown the socket as provided with a key 15, but this is not always employed. 70

16, indicates the shade holder which has a central opening 17, screw-threaded.

18, denotes a plurality of set-screws by 75 which a shade or bowl may be held to the ring or holder 16.

The lamp socket 12 is detachably connected with the holder 16 by screwing its lower threaded end into the threaded central opening 17 in the holder.

The cover 10 is made of a height to exactly fit between the under surface of the band or rib 14 on the socket 12, and the top of the holder 16, at its outer edge, when the socket is screwed into the threaded opening 17 in the shade holder, and the downwardly curved lower edge of the cover conforms to the curvature at the outer extremity of the top of the shade holder, giving the fixture the outward appearance of a one piece article when in use. 90

In assembling the parts, the lower part of the socket 12, is passed into the top opening of the cover 10, and where the key 15 is provided on the socket, it is passed into the slot 11, in the cover, allowing the top of the 95 cover to contact with the under surface of the band or rib 14, on the socket; while in this position the lower end of the socket is screwed into the threaded opening of the shade holder 16, the cover being thus securely 100 clamped in place, entirely covering the socket below the band or rib 14, and giving a finished and ornamental appearance to the fixture.

I claim as my invention:

1. The combination with a lamp socket provided with an exterior annular band adjacent its upper end, and a shade-holder detachably connected to the lower end of the socket, of a socket-cover comprising a 110

circular hollow body open at both ends, the upper half being of uniform diameter and the lower half curved outwardly, said cover being clamped between said annular band 5 upon the socket and the top of said shade-holder.

2. In a lighting fixture, the combination of a lamp-socket provided with an exterior annular band adjacent its upper end, 10 and a screw thread adjacent its lower end, a shade holder provided with a central threaded opening and set screws for clamping a

shade, a socket cover comprising a circular hollow body open at both ends, the upper half being of uniform diameter and the 15 lower half curved outwardly, said cover being clamped between said annular band upon the socket and the top of said shade holder when the threaded end of said socket is screwed into the central opening in the 20 shade-holder.

Signed by me this 27 day of August 1917.

CURTIS A. LIMBACH.
